C. K. CHATTERTON.
FAN ATTACHMENT FOR SMOKE STACKS.
APPLICATION FILED JUNE 29, 1912.

1,072,698.

Patented Sept. 9, 1913.

UNITED STATES PATENT OFFICE.

CHARLES K. CHATTERTON, OF LONG PRAIRIE, MINNESOTA, ASSIGNOR OF ONE-FOURTH
TO PERRY KNAAPP, OF LONG PRAIRIE, MINNESOTA.

FAN ATTACHMENT FOR SMOKE-STACKS.

1,072,698.

Specification of Letters Patent.

Patented Sept. 9, 1913.

Application filed June 29, 1912. Serial No. 706,761.

To all whom it may concern:

Be it known that I, CHARLES K. CHATTERTON, citizen of the United States, residing at Long Prairie, in the county of Todd and State of Minnesota, have invented certain new and useful Improvements in Fan Attachments for Smoke-Stacks, of which the following is a specification.

My invention relates to new and useful improvements in motors and more particularly to that class of motors embodying an elongated shaft having radially directed propeller blades adapted to be acted upon by a passing current of air, smoke, steam, water or like fluid to rotate the shaft and thereby furnish power for the driving of any preferred type of machinery.

More particularly, the object of my invention is to provide a novel means for mounting a motor of the above described type in the stack or flue of a furnace or other heating device in such a manner that it is driven by the products of combustion by the fire passing through the stack on their way to the air.

A still further object of my invention is to provide a novel means of mounting the propeller blades upon the propeller shaft and also a peculiar and effective manner of arranging the blades upon the shaft.

With these and other objects in view, my invention will be more fully described, illustrated in the accompanying drawing, and then specifically pointed out in the claims which are attached to and form a part of this application.

In the drawing: Figure 1 is a central longitudinal section of a conventional form of smoke-stack, showing my motor applied thereto; Fig. 2 is a transverse section on the line 2—2 of Fig. 1; Fig. 3 is a perspective view of one of the blade holders by means of which the propeller blades are mounted upon the shaft.

Corresponding and like parts are referred to in the following description and indicated in all the views of the drawing by the same reference characters.

The preferred embodiment of my invention includes an elongated frame or housing preferably rectangular in shape, formed of metal, and provided at its ends with spiders 11 and 12 in which is journaled the propeller shaft 13 carrying a plurality of propeller blades 14.

It will of course be understood that a motor of this type may be positioned within a stack without the intervention of the frame or that it may be employed equally as well in a horizontally extending flue leading to the stack, or in both, the propeller shaft in this case being formed in two sections operatively connected to each other either by a gimbal joint or by beveled gears. It will also be apparent that the propeller shaft and its blades may be employed either with or without the frame as a water motor, being either wholly or partially submerged in a swiftly flowing stream or river. I do not therefore wish to limit myself to the specific use of a propeller in a smoke-stack vertical or otherwise.

Referring more specifically to the drawing, which shows the motor mounted in a conventional form of smoke-stack 15 into which leads the flue 16, it will be seen that the lower spider is provided centrally with a socket 17 in the base of which is positioned a wear plate 18 preferably of highly tempered steel or other wear resisting metal, and across the upper end of which is bolted or otherwise secured a plate 19 provided with a centrally formed bore, the bore and plate 18 co-acting to form a bearing for one end of the propeller shaft. The spider 12 is centrally provided with a cylindrical socket 20 forming a bearing for the other end of the shaft.

The propeller shaft may be formed of wood or metal as preferred, the material of which it is made depending upon the use to which the motor is to be put and the degree of heat or strain which it must withstand. If formed of wood its ends are preferably inclosed in metallic caps 21 and pins 22 extend centrally from the ends of the shaft through the caps and through the bores of the plate 19 and of the spider 20, the lower end of that pin passing through the plate 19 bearing upon the upper face of the plate 18 to produce a practically frictionless bearing. A suitable washer 23 may be interposed between the upper end of the propeller shaft and the spider 20 to take up wear between the same. If the shaft is formed of metal, its ends are preferably somewhat reduced to engage in the bearings in the same manner as the pins.

An opening 24 is formed through one side of the lower portion of the stack for the

passage of a belt or chain 25 for transmitting power from the propeller to the machine to be driven, this belt passing within the stack and about a pulley or sprocket 5 wheel 26 keyed upon the shaft adjacent its lower end.

The blades 14 are mounted upon the propeller shaft in spaced apart pairs, as shown, each pair being secured to the shaft by 10 means of a blade holder designated as a whole by the numeral 27. This holder may be formed of either wood or metal as desired but is preferably formed of the same material as the propeller shaft. Each of 15 the blade holders comprises a body member formed in a single piece and having a centrally formed bore extending through it at an angle to give it, when mounted upon the shaft, a longitudinal inclination equal to the 20 desired inclination of the propeller blades to the shaft. The ends of this body member are beveled or otherwise formed to provide wedge-shaped blade engaging arms 28 and 29 having axial blade receiving slots 25 30, the arms being reversely formed to bring the slots of each member at right angles to each other. The propeller shaft is passed through the bores 31 of these 30 blade holders and the holders are bolted 35 or otherwise secured against both longitudinal and rotary movement upon the shaft. The blades previously designated by the numeral 14 are preferably formed of sheet metal and are secured to the blade holders 40 by passing their inner edge portions into the slots 30 of the holders and securing them therein by bolts, rivets or other preferred means 32.

The blades are so shaped that their inner and outer edges form arcs of concentric circles, while their end edges extend radially to their inner and outer edges. The blades are curved longitudinally from end 45 to end. As previously mentioned, the propeller blades are secured to their shaft in spaced pairs and the blades of each pair are directed at right angles to each other and extend diametrically from opposite sides of the shaft. Moreover, one blade of 50 each pair is inclined downwardly, while the opposite blade is inclined upwardly. The pairs of blades are also peculiarly arranged with respect to each other, for instance, each pair is so arranged that a line drawn centrally through its blades and shaft would

extend at right angles to a line similarly drawn through an adjacent pair of blades. Again the pairs of blades are so arranged that the blades of alternate pairs are in alinement with each other although each 60 of the alined blades is inclined oppositely to the adjacent blades alined therewith.

The peculiar arrangement of blades in oppositely disposed, or oppositely inclined pairs and the arrangement of these pairs in 65 the peculiar manner above described, greatly increases the efficiency of the propeller over the common form of propeller now in use in water motors and the like. Moreover, the specific formation of the blades, when used 70 in a cylindrical casing of the character described, effectively offers a relatively large area of contact for the pressure of the fluid passing through the casing and consequently affords great efficiency. 75

Having thus described the invention, what is claimed as new is:

1. A motor including a rotor shaft, and a plurality of propeller blades secured to said shaft and extending radially therefrom, the 80 inner and outer edges of said blades being arcs of concentric circles of which the end edges are radii, said blades being arcuately curved longitudinally in planes at right angles to the planes of their outer edges by 85 bending them uniformly from end to end.

2. A motor including a vertical rotor shaft, a plurality of propeller blades arranged in oppositely disposed pairs, and means for securing said blades to the shaft, said means 90 including blade holders provided centrally with bores through which the shaft extends, said bores being so formed as to incline the holders at an acute angle to the shaft, the end portions of said holders being beveled 95 to form wedge-shaped blade receiving members which are slotted axially to seat the blades, said wedge-shaped members being oppositely formed to incline the blades carried by each holder in reverse direction, the 100 inclination of the blade holders with respect to the shaft positioning one blade of each pair above the other blade and both blades at an angle to the shaft.

In testimony whereof I affix my signature 105 in presence of two witnesses.

CHARLES K. CHATTERTON. [L. s.]
